CLAIM

[21] Appl. No.: 843,645

The ornamental design for a stereoscopic viewer, as shown and described.

[22] Filed: Oct. 19, 1977

DESCRIPTION

[51] Int. Cl. .... D16—06
[52] U.S. Cl. D16/12
[58] Field of Search D16/12, 14; 350/130, 350/133, 134, 135, 139, 141, 142, 143

FIG. 1 is a perspective view of a stereoscopic viewer, showing our new design;
FIG. 2 is a front elevational view thereof;
FIG. 3 is a right side elevational view, the left side being a mirror image thereof;
FIG. 4 is a top plan view thereof.
FIG. 5 is a bottom plan view thereof; and
FIG. 6 is a rear elevational view thereof.
